UNITED STATES PATENT OFFICE

114,749

DESIGN FOR A GAME DEVICE

John Brophy, Caracas, Venezuela

Application July 27, 1938, Serial No. 78,786

Term of patent 14 years

To all whom it may concern:

Be it known that I, John Brophy, a citizen of the United States, residing at Caracas, Venezuela, South America, have invented a new, original, and ornamental Design for a Game Device, of which the following is a specification, reference being had to the accompanying drawing, forming part thereof.

Fig. 1 is a plan view of a game device, showing my new design; and

Fig. 2 is a cross section of the same taken on the line 2—2 of Fig. 1.

I claim:

The ornamental design for a game device, as shown.

JOHN BROPHY.
